UNITED STATES PATENT OFFICE.

WARREN C. FULLER, OF YARMOUTH, MASSACHUSETTS.

SURGE-RELIEVER.

SPECIFICATION forming part of Letters Patent No. 272,874, dated February 27, 1883.

Application filed August 21, 1882. (No model.)

To all whom it may concern:

Be it known that I, WARREN C. FULLER, of Yarmouth, State of Massachusetts, have invented an Improved Surge-Reliever, of which the following is a specification.

This invention relates to elastic yielding relievers to which cables and hawsers are attached, in order that such elasticity may materially lessen the strain resulting from the force of the surges to which the vessel or other body is subjected which is anchored or held by such cables or hawsers; and the invention consists in the construction and combination of the various devices embodied therein, as hereinafter more particularly and fully set forth and claimed.

In the accompanying drawings, Figure 1 is a side elevation of my improved reliever, shown as secured to a vessel's deck, and also showing, partly by dotted lines, an anchoring-chain attached to the reliever. Fig. 2 is a top or plan view of the reliever, as shown in Fig. 1. Fig. 3 is a detached sectional elevation, showing the upper portions of two of the elastic columns in elevation, the telescoping tubes and cap in section, and the upper portion of two of the holding-rods in elevation and as secured in the inner tube. Fig. 4 is a transverse section taken through the buffers and their guide-rods and through the anchoring-rods, as in line $z z$, Fig. 1. Fig. 5 is a longitudinal section of one of the buffers, and showing the abutting plates and cap and follower of the frame, also in section, and the guide-rod in elevation. Fig. 6 is a top or plan view of the supporting-frame, and showing the hooks of the anchoring-rods and the guide-rods.

In said views, $a a$ represent the side pieces of the frame, in which I secure the buffers. A cap, b , and base d are secured upon the respective ends of $a a$ by the buffer guide-rods e , as shown. The buffer-columns B , of which four are preferably employed, are composed of the hollow cylindrical elastic sections f , of rubber, separated by the circular supporting flanged disks g . The buffers, thus composed, are arranged upon and guided by rods e , between head b and follower c , which latter slides freely on said rods, both said cap and follower being either recessed or provided with flanges to receive and support the abutting section g , as

shown in Fig. 5. The anchoring-rods x (of which there are four) are each formed at the upper end with a hook, y , and diverge as they extend downward and pass through follower c , to which they are secured by screw-nuts, as shown in Fig. 1. A short but strong tube, v , is firmly secured in cap b , and a larger and closely-fitting tube, t , is arranged to slide telescopically in tube v . The rods x are placed in position in tube t , as shown in Figs. 2, 3, 6, when melted lead or other suitable metal is poured therein, filling all the spaces inside said tube, after which, if necessary, the lead or other material may be closely calked or tamped to render said tube water-tight. Cap b is bolted to plate h by bolts i , as shown in Fig. 1, and said plate h is bolted to deck j and deck-beams k by bolts l . Upon plate h is rigidly secured, by bolts i , the sheave-case, formed with a bed, n , and the side cheeks, $m m$, in which latter are secured the pins $s s$, on which sheaves or rollers $p p$ rotate. The cable-chain, hawser, or other means of anchorage is secured to each of the hooks y , as shown at A, Fig. 2. Any desired number of the buffer-columns B may be employed; but I prefer four, as stated.

By employing a plurality of anchoring-rods, x , the plane of follower c is always held parallel with cap b and at right angles to the axis of columns B ; besides which, the danger resulting from defects in said rods is decreased, as they are intended to be of such size and strength that either two shall be equal to the strength of the anchoring-chain; and hence, if one or two of said rods should fail from any defect, the others are equal to the chain in strength.

By means of the fixed tube v and sliding tube t , with rods x packed therein, as described and shown at z , and with bed h closely fitted to deck j , water cannot pass below the deck, tube t being of such length that its lower end will still be in tube v when the ultimate strain is exerted upon columns B . If desired, the sides $a a$ may be secured directly to bed h , in which case rods e would pass through said bed.

By means of sheaves p the reliever can be placed in a vertical position below the deck, leaving the same clear, except the sheave-case $m m$, and the chain or hawser A may lead out at the bow, as in case of riding at anchor or when being towed; or it may lead aft, as in

case of its being used to tow another craft, and the strain upon rods *x* is always in the line of the axis of tube *t*.

I am aware that a variety of elastic surge and other relievers have been invented and patented, and hence I do not broadly claim a reliever adapted to be connected with a hawser or chain, my invention being confined to the specific construction and arrangement embraced in the claims.

I claim as my invention—

1. The combination of elastic columns *B*, mounted upon guide-rods *e*, follower *c*, mounted upon said rods and arranged to compress said columns, and anchoring-rods *x*, converged at hooks *y* and diverged at followers *c*, and secured therein, substantially as specified.

2. In a surge-reliever, the combination of cap *b* of the supporting-frame, outer tube, *v*, secured water-tight therein, tube *t*, arranged to fill and slide in tube *v*, and the anchoring-rods *x*, arranged and secured rigidly and water-tight in tube *t*, whereby said anchoring-rods and tube *t* may move linearly in tube *v* and cap *b* without admitting water through the same, substantially as specified.

3. In combination with elastic columns *B*, arranged upon guide-rods *e*, follower *c*, arranged to act upon and compress said columns,

and anchoring-rods *x*, secured in said follower 30 and converged at the opposite end, the rolls *p*, mounted in supporting-case *m* and arranged on opposite sides of hooks *y* of said rods to receive the chain *A* attached to said hooks, substantially as specified.

4. The combination of side supports, *a a*, cap *b*, and head *d*, properly secured together by guide-rods *e*, said rods and elastic columns *B* thereon mounted, follower *c*, arranged to act against said columns, anchoring-rods *x*, secured 40 to said follower and passing through cap *b*, and rolls *p*, arranged in their supporting-case on either side of hooks *y* of rods *x*, all substantially as specified.

5. In a surge-reliever, a deck plate or bed, 45 a frame to support the elastic buffers arranged below such bed, elastic columns or buffers supported by such frame, a follower to act on or compress said columns, anchoring-rods secured to such follower and passing above the 50 deck plate or bed, and sheaves or rolls over which to carry the chain or hawser from a vertical to a horizontal line, substantially as specified.

WARREN C. FULLER.
